[57] ABSTRACT

A strap wrench for grasping and rotating articles, such as cylindrical spin-on filters, comprises a support, a cam member rotatably mounted in the support and a flexible strap having one end attached to the cam member and a second end threaded therethrough. An arcuate surface is formed on the support to abut and substantially conform to outer cylindrical surface portions of the rotated article. Such arcuate surface cooperates with the strap to grasp the article, upon rotation of the cam member, to uniformly distribute a torquing force therearound and to prevent damage thereto.

FLEXIBLE STRAP WRENCH

BACKGROUND OF THE INVENTION

Numerous types of strap wrenches are employed for removing spin-on oil and fuel filters from internal combustion engines. Such wrenches exhibit disadvantages, such as their inability to uniformly distribute a torquing force fully around a filter to expeditiously and easily remove or install same. In addition, the wrenches often times crush or otherwise damage the filter upon rotation thereof due to the filter's thin-wall shell construction.

Damage to the filter's shell during removal thereof may be sufficiently severe to prevent the wrench from gripping the filter. In such instances, the service man normally drives a bar or heavy screwdriver through the filter and cranks same to break it loose. This procedure is inconvenient, time-consuming and allows uncontrolled escape of fuel or oil.

During installation, replacement filters are customarily tightened by hand, without the aid of a strap wrench, to alleviate the damage and related problems. However, since the filters are subjected to severe vibrations or pulsations during engine operation, they have a tendency to loosen to thus induce oil or fuel leakage. The problem is particularly apparent with respect to filters employed in connection with high-performance, fuel injection pumps. Such pumps produce high intensity pressure waves which are transmitted through the filter to induce loosening thereof. Loosening of the fuel filter presents an especially dangerous situation due to the fire hazard involved.

SUMMARY AND OBJECTS OF THIS INVENTION

An object of this invention is to overcome the above described problems by providing an economical and efficient strap wrench adapted to expeditiously grasp and rotate cylindrical articles, such as spin-on filters, without causing damage thereto. The strap wrench comprises a support having a cam member rotatably mounted thereon and a flexible strap having one end attached to the cam member. The support has an arcuate surface formed on a base thereof which substantially conforms to the periphery of the article. The cam member, when rotated, cooperates with the strap to uniformly distribute a torquing force around the article and to prevent damage thereto.

BRIEF DESCRIPTION OF THE DRAWINGS

Further objects of this invention will become apparent from the following description and accompanying drawings wherein:

FIG. 1 is a top plan view of a flexible strap wrench embodiment of the present invention;

FIG. 2 is a side elevational view of the strap wrench;

FIG. 3 is a sectional view of the strap wrench, but illustrating the wrench as it would appear during the installation of a spin-on replacement filter; and

FIG. 4 is a view similar to FIG. 3, but illustrating the strap wrench as it would appear during the removal of a spent filter.

DESCRIPTION OF THE PREFERRED EMBODIMENT

Referring to FIGS. 1 and 2, the illustrated strap wrench embodiment essentially comprises a support 10, having a cam member 11 rotatably mounted therein, and a flexible strap 12 attached at one end thereof to the cam member. The U-shaped support (FIG. 2) comprises spaced upstanding legs 13 and 14, secured together by means of an intermediate base plate 15. The plate defines an arcuate surface 16 thereon, subscribed by a radius having its center at point X in FIG. 1, which faces away from the support and in general concave relationship thereto.

Since the outer diameters of a series of filters will vary in size, arcuate surface 16 preferably corresponds to the largest filter diameter in the series for which the wrench is to be used. The full accommodation of the largest diameter provides for a slight deflection of the shell of the smaller filters, without damage, so that they will assume the shape of arcuate surface 16. Arcuate surface 16 thus provides for the servicing of a wide range of filter sizes, while yet assuring maximum possible surface contact between the arcuate surface and the filters.

The contact area provided by the strap wrench of this invention is substantially larger than the contact areas which are occasioned by conventional strap wrenches. In particular, arcuate surface 16 cooperates with strap 12 to substantially fully circumvent and distribute a torquing force around the filter whereas prior art constructions normally concentrate high torquing forces at small areas on the filter. In FIG. 1, angle α defining the arcuate surface is preferably selected from the approximate range of from 30° to 90° , e.g. 65° as shown.

Cam member 11 comprises a pair of laterally spaced cylindrical bearing portions 17 and 18 rotatably mounted in bores formed in legs 13 and 14, respectively. Snap rings 19 and 20 are suitably positioned in annular grooves formed on the cam member to prevent axial movement thereof. The bearing portions are connected together by an intermediate cam means 21 which is offset radially with respect to a central rotational axis Y of the cam member.

An elongated pin 22 is secured to legs 17 and 18 of the cam member to attach the looped and stitched first end of flexible strap 12 thereto. It should be noted that the pin is offset with respect to axis Y and preferably diametrically opposed with respect to cam means 21 to provide a slot therebetween adapted to receive a second, free end of the strap therethrough.

The strap preferably comprises an elongated, flat band constructed of a flexible and durable woven fabric such as nylon. The strap has a high tensile strength, but yet exhibits sufficient flexibility to envelope and frictionally grasp the exterior surface of a cylindrical article, such as a spin-on filter F illustrated in FIGS. 3 and 4.

Referring to FIG. 3, the strap wrench is shown in its operative position for installing a spin-on filter F. Initially, the workman positions arcuate surface 16 in abutting relationship with the filter. The free end of strap 12 is then manually threaded through the slot defined between cam means 21 and pin 22 (FIG. 1) and semi-tightened. A square socket 23 is formed in

each of bearing portions 17 and 18 of the cam member to accommodate a mating torquing tool.

Upon clockwise rotation of the tool and cam member about axis Y in FIG. 3, cam means 21 and pin 22 will rotate, as shown, to shorten the effective length of the strap portions forming a circular continuation of arcuate surface 16. Once the filter is grasped snugly, the entire strap wrench is moved clockwise about axis X to tighten the filter a predetermined amount.

FIG. 4 illustrates the removal of a spent filter F by reversing the above described sequence of operation. In particular, cam member 11 is rotated in a counter-clockwise direction to shorten the strap and to grasp the filter by applying a substantially uniform torquing force therearound.

What is claimed is:

1. A strap wrench for grasping and rotating cylindrical articles comprising
 a support including means defining a substantial arcuate surface thereon, facing away from said support in general concave relationship thereto, generally conforming to the outer diameter of an article to be rotated,
 a cam member rotatably mounted about a central axis thereof in said support, including cam means,

10 and the position whereat said strap is attached to said cam member are diametrically opposed on said cam member on respective sides of the central axis thereof.

15 2. The invention of claim 1 wherein said cam means and the position whereat said strap is attached to said cam member are diametrically opposed on said cam member to define a slot therebetween adapted to receive a second, free end of said strap therethrough.

3. The invention of claim 1 wherein said support is U-shaped to comprise a base defining said arcuate surface thereon and spaced legs having said cam member rotatably mounted therein.

4. The invention of claim 3 wherein said cam member comprises spaced, cylindrical bearing portions each rotatably mounted in a respective one of said legs 20 and means for preventing axial movement of said cam member relative to said central axis and said support.

5. The invention of claim 1 wherein said arcuate surface is defined by an angle selected from the approximate range of from 30° to 90°.
